Genus and species: *Dianthus caryophyllus*.
Variety denomination: 'KLEDP14216'.

BACKGROUND

The present invention comprises a new and distinct variety of *Dianthus*, botanically known as *Dianthus caryophyllus*, and hereinafter referred to by the variety name 'KLEDP14216'. 'KLEDP14216' originated from a cross-pollination between the proprietary female *Dianthus* parent 'DCP 2006 0122' (unpatented) and the proprietary male *Dianthus* parent 'DCP 2007 0092' (unpatented) in May 2008 in Stuttgart, Germany.

The seeds from the cross were sown and plants were grown in a greenhouse for evaluation, where an individual plant designated 'KLEDP14216' was selected from the group of plants in May 2009 in Stuttgart, Germany. In October 2009, 'KLEDP14216' was first vegetatively propagated by vegetative cuttings. 'KLEDP14216' was found to reproduce true to type in successive generations of asexual propagation in Stuttgart, Germany via vegetative stem cuttings.

SUMMARY

The following are the most outstanding and distinguishing characteristics of this new variety when grown under normal horticultural practices in Stuttgart, Germany.

1. Purple and dark-red double flowers; and
2. A little hanging character but first upright, stems and flower stems are more hanging from beginning of the flowering.

DESCRIPTION OF THE PHOTOGRAPH

This new *Dianthus* plant is illustrated by the accompanying photograph of a plant approximately 10 to 12-weeks old and grown in a glass greenhouse in Stuttgart, Germany.
